UNITED STATES PATENT OFFICE.

HENRY W. AVERY AND WALLACE S. JUDD, OF CLEVELAND, OHIO.

SHEET-METAL BARREL.

972,797.

Specification of Letters Patent. Patented Oct. 18, 1910.

Application filed January 20, 1908. Serial No. 411,597.

To all whom it may concern:

Be it known that we, HENRY W. AVERY and WALLACE S. JUDD, both citizens of the United States, and both residing at Cleve-

land, in the county of Cuyahoga and State of Ohio, have invented a certain new and useful Improvement in Sheet-Metal Barrels, of which the following is a full, clear, and exact description.

10 The object of the present invention is to provide an improvement in metallic barrels whereby it is rendered possible to construct such barrels with a bilge; and it is further an object to make certain other improvements in the construction of metallic barrels by which the manufacture of such articles may be facilitated and the quality of the article improved, as will appear below.

Referring to the accompanying drawings, 20 which serve to illustrate our invention, Figure 1 is a perspective view of a sheet metal blank such as we use in the manufacture of a section of the barrel. Fig. 2 is a perspective view showing the sheet blank drawn 25 downward to give the swell or barrel shape thereto,—a bilge being formed in the center thereof during the drawing process. Fig. 3 is a perspective view of the barrel section shown in Fig. 2 with a reëntrant rib bent 30 inwardly at the central zone or bilge portion of the barrel. Fig. 4 is a fragmentary detail showing the barrel head, as it is first fitted onto the barrel end after the sections have been secured, the wearing band which 35 is placed over the chime after the head is in position being shown adjacent to the chime in this figure. Fig. 5 is a side elevation partly broken away and partly in section showing the barrel after the longitudinal sections have been secured together,—the upper section being shown as provided 40 with longitudinal stiffening flutes. Fig. 6 is a section on the line 6—6 of Fig. 5. Fig. 7 is a detailed section showing the reinforcing band about the bilge of the barrel.

In the making of our barrel we have endeavored to produce a construction which shall be not a mere theoretical invention or one which may be made only at such an 50 extraordinary cost as to be useless to the art, or which would fail to have the ordinary capabilities of use which are demanded by the trade, but rather an article which shall be both possible to make by the present 55 known methods of sheet metal drawing and having those features of construction which

render it capable of taking the place of any ordinary barrel now in use, and shall be within the limit of cost imposed by the trade conditions.

In producing our barrel we use a substantially rectangular sheet metal blank A such as that shown in Fig. 1, and draw it down to the shape of the half barrel section B shown in Fig. 2, in which the swell of 60 half the barrel is given to the blank and the metal at the same time drawn down to give a bilge C in the middle thereof. Preferably we draw a circumferential reëntrant rib D into the bilge portion of the section, 65 increasing in depth from the edges of the section toward the center thereof. The edges D' formed with the creation of this rib are parallel and serve as rolling edges when the barrel is on its side, in the event 70 the band D² be not used. This rib D is subsequently made of even depth throughout the entire circumference, after the two sections B are secured together, as will be 75 seen in Fig. 6. This rib D is for the primary purpose of resisting the inward or collapsing pressure on the barrel, a matter of considerable importance when certain classes of oil are stored in metallic barrels, as is 80 well known to persons familiar with such matters. For the purpose of resistance to the expansive pressure of the liquids and gases contained in the barrel, we prefer to place a band D², as shown in Fig. 5, around 85 the barrel about the bilge and outside of the rib D, the ends of the band being secured in any suitable manner, and the band held against endwise displacement by means of ribs D³ fitted inside of and abutting against 90 the edges D' of the channel D⁴ behind the 95 rib D. The band D² is shown as perforated to allow free expansion of the air inclosed in the channel D⁴, and to permit surplus coating material to flow out. This band is particularly valuable as giving a reinforced 100 wearing surface at a part where the barrel is subjected to great wear. Further its use completes the bilge surface, making it effective for all the purposes for which a bilge is useful, such as tilting and spinning 105 the barrel about on its side. All of these advantages of the perfect bilge shape are thus had without any diminution by reason of the presence of the stiffening rib D.

It will be seen in the particular structure 110 here shown that we leave two side edges of the blank flat, which flat edges form flanges

E on the barrel section, to be used subsequently for forming a seam with the mated section.

We may provide longitudinal flutes or 5 ribs F in the body of the sections, as is shown in Figs. 5 and 6, for the purpose of stiffening the sheet metal and increasing its 10 resistance to distortion, but this is not an essential thing. The bung, if one is used, may be set into the central rib D of one of the 15 sections after the manner shown in Fig. 5, and thus be out of the way so as not to interfere with the handling or rolling the barrel. The two barrel sections may then be secured 20 together by forming the double fold seam G shown in Fig. 6, which seam is rolled down tightly so as to form a liquid tight union between the two sections. The rib D is then made the same depth at the double seam 25 joint of the two sections which it has in the center of each section, making a continuous rib of even depth. The barrel heads H are then secured in place. These barrel heads 30 are preferably shaped so as to be inset and lie within the end of the barrel body when in position, and are provided with a circumferential groove I into which the edge of the 35 barrel end shall be tightly fitted. After the barrel heads are in position a series of circumferentially disposed interlocking elevations and depressions R are made in the 40 walls of the barrel body and the walls of the groove of the barrel head, which indentations serve to draw the metal joints even 45 tighter and to securely hold the barrel ends in place. We also, preferably, place a grooved or hook-shaped channel rim J on the chime of the barrel and shrink it thereon. The band J is designed to reinforce the 50 chime and receive the great wear to which the barrel is subjected by being dropped on its ends. The exterior wall of the band J is perforated, the perforations receiving the bulging projections by which barrel body 55 and head are interlocked. This barrel head secured in this manner we find to be far tighter than barrel heads secured by spinning process, since the spinning process rolls the metal ahead of the spinning chucks and loosens the joint. The finished barrel is 60 then in condition to be handled in the manner in which any ordinary barrel is handled, since it has a bilge by which it may be tilted, chimes of proper strength to permit of its 65 being stood upon end, and a suitable rolling surface at its bilge, while the bung is inset so as not to interfere with or be injured by the handling of the barrel.

It is found that this structure is exceedingly rigid and strong and is capable of 65 withstanding the roughest treatment and has practically an unlimited life. We wish particularly to call attention to the fact that this construction of barrel may be made of full size with a bilge, by the present known

methods of metal drawing, a thing which it is impractical or too expensive to accomplish with any other proposed structure of metallic barrel. Every sheet metal worker knows that it has been heretofore impractical to construct a barrel of ordinary size if the barrel were made of two transverse sections and the metal blanks be drawn in cup shape to form the sections. The strain would be too great for the material and the expense of spoiled metal would be too great, even if it were possible to occasionally accomplish the feat of successively shaping the blank into form. The amount of stretching, however, necessitated by our construction and method of procedure, is so small that the bilge may be formed after the manner shown in Fig. 2 out of even galvanized sheet metal, if desired, without endangering the coating in the least, whereas there is no other construction of bilged metallic barrel proposed which could possibly be made from a galvanized or metal coated blank, and, as every one is aware, the galvanizing or coating of the metal, after it has been shaped into the finished form, is a very expensive proposition for the barrel manufacturer to consider, and therefore such prior proposed constructions of barrels and such proposed methods of making barrels could not be properly called contributions to the art, since they serve no purpose whatever toward advancing the same. We are aware that it has further been proposed, in addition to the making of small kegs or articles of short depth out of drawn cup shaped, transverse sections, to roll a sheet into cylindrical form about the full size of a barrel and secure it with a seam at the meeting edges of the sheet. This, however, does not produce an article which is of any value to shippers, since it is impossible to handle readily a barrel of full size of such construction owing to the lack of bilge. The principal demand for and use of metal barrels will be in shipment of oils and liquids which are quite heavy and which, when once stowed in a cylindrical barrel of full size, would be so unwieldy as to require two or more men to handle. It is therefore absolutely essential that a metallic barrel, in order to be of any utility in the field in which it is designed to be used, shall have a bilge, and the construction of barrel which we have designed is, so far as we are aware, the only construction by which it is possible to produce a barrel at low cost, of ordinary size, of sheet metal, which shall have a bilge.

Any construction of bilged metallic barrel heretofore proposed which involves "stamping" or "pressing" has necessarily been made of small pieces, in order to take care of the surplus metal which buckles up around the edges of what might be called the

"staves." All of the methods involving "stamping," "pressing" or "rolling" necessarily waste metal, as is well known to every person having any practical knowledge of metal working, this waste either appearing in material sheared off, or in the usual and unnecessary flutes in the barrel end (which are not only waste metal but interfere with a successful head joint) and also in the heavy slugs or thicknesses and buckles along the edges of the staves. Further, in any rolling method the barrel body must be removed from the rolls endwise, necessitating the removal of the standards. In rolling, also, the weak spots in the metal will be thinned out, whereas by our drawing method the thickness is made the same throughout.

While the detailed improvements, such as the reëntrant rib about the center of the barrel for the purpose of stiffening the barrel and receiving the bung, and the improvement in the method of securing the barrel end, are in themselves valuable, nevertheless we regard the method of shaping and assembling the barrel in longitudinal sections to be the most important contribution to the practical manufacture of barrels, and it is to this that we desire to draw our claims broadly.

Having thus described our invention, we claim:

1. A longitudinal half barrel section formed of drawn metal, said section being of substantially equal thickness throughout, and having a centrally drawn bilge, and having along its longitudinal edges, extending from end to end, outwardly turned flanges.
2. A metallic bilge barrel formed of two drawn longitudinal sections, the metal whereof is of substantially equal thickness throughout, each section having a centrally disposed bilge and having an outwardly turned flange along each of its longitudinal edges, said sections being secured together by seams formed by double folding together the said flanges.
3. A sheet metal barrel formed of two

drawn longitudinal sections, the metal whereof is of substantially equal thickness throughout, each section being provided with a centrally disposed bilge, and each section being formed with an outwardly turned flange along each of its longitudinal edges, and the two sections being secured together by a seam formed by double folding said outwardly turned flanges and by pressing the seam inward so that the outer surfaces of said seams are substantially regular continuations of the curved surface of the barrel, and said barrel having in the centrally placed bilge a circumferential re-entrant rib of substantially equal depth throughout.

4. A sheet metal barrel having a head fitted to the end of the body portion, one of said parts being provided with a groove into which the edge of the other part is fitted, and a channel band fitted over the chime formed by the head and the end of the body, said channel band having perforations through one side thereof and crimps or corrugations formed through the overlapping thicknesses of the chime and projecting into the said perforations.

5. A sheet metal barrel section having a drawn bilge in the middle portion thereof and an inset stiffening rib having its full depth at the middle portion of the section and diminishing in depth toward its ends near the edges of the section where it becomes flush with the body.

6. A sheet metal barrel section having a drawn bilge therein and outwardly directed flanges at each edge, a stiffening rib for the said section having its full depth at the middle portion thereof and diminishing in depth toward its ends at the edge of the section where it becomes flush with the body.

In testimony whereof, we hereunto affix our signatures in the presence of two witnesses.
